United States Patent Office

Des. 203,070
Patented Nov. 30, 1965

203,070

BRACKET OR SIMILAR ARTICLE

Thomas R. Symington, 333 E. 53rd St., New York, N.Y.

Filed Feb. 25, 1965, Ser. No. 83,981

Term of patent 14 years

(Cl. D54—1)

Fig. 1

Fig. 2

Fig. 4

Fig. 3

Fig. 5

Fig. 6

FIGURE 1 is a top plan view of a bracket or similar article showing my new design;

FIGURE 2 is a view in perspective thereof;

FIGURE 3 is a front elevational view thereof;

FIGURE 4 is a side elevational view thereof;

FIGURE 5 is a bottom plan view thereof; and

FIGURE 6 is a rear elevational view thereof.

I claim:

The ornamental design for a bracket or similar article, substantially as shown.
